UNITED STATES PATENT OFFICE

2,602,558

PUSHER ALIGNING MEANS FOR CONVEYERS

Chester Graham Clark, Detroit, Mich., assignor
to The Udylite Corporation, Detroit, Mich., a
corporation of Delaware

Application August 9, 1951, Serial No. 241,146

12 Claims. (Cl. 214—89)

1

The present invention pertains to a novel mechanism for alining work pieces on a conveyor rail with respect to the work pushers on the rail. The invention is here disclosed with reference to plating apparatus, although not necessarily limited thereto as will later appear.

The work is suspended from the rail by hooks or carriers, and the latter is advanced along the rail by pushers attached to an intermittently moving chain. In order to perform an operation on the work, a separable section of the rail is moved transversely to bring the work pieces thereon to the treating apparatus. In a plating operation, this apparatus is one or more tanks disposed below the movable rail section.

When the movable section is returned to align with the main rail, the work carriers on the section often lose their proper relation to the corresponding pushers on the chain. Such carriers either collide with or fall behind the corresponding pushers rather than in front of them, and the proper functioning of the conveying apparatus is thereby interrupted until corrections can be made.

The principal object of this invention is to overcome this difficulty by bringing the carriers on the movable rail section into proper position in front of the pushers. The movable rail section is carried by a properly guided and actuated chassis. To accomplish the stated object of the invention, the chassis carries auxiliary pushers or work-moving members which are actuated on movement of the chassis to adjust the work carriers to proper position relatively to the chain pushers as the movable rail section returns to the chain.

The work-moving members are in the nature of rocker arms pivotally mounted on the chassis. They are pivotally attached to an actuating rod slidably mounted on the chassis and parallel to the rail. The ends of the rod engage cams on the frame structure in which the chassis is mounted. One of the cams shifts the rod to effect the aforementioned adjustment of the work carriers on the movable rail section, and the other cam reverses the movement of the rod or sets the auxiliary work-moving members as the movable rail section is moved away from the pusher chain.

The invention is fully disclosed by way of example in the following description and in the accompanying drawings in which:

Figure 1 is a diagrammatic plan view of an installation embodying the invention;

Figure 2 is a plan view of the device of the invention;

2

Figure 3 is a vertical elevation thereof, partly in section;

Figure 4 is a section on the line 4—4 of Figure 3;

5 Figure 5 is a section on the line 5—5 of Figure 3;

Figure 6 is a detail plan view showing the position of parts when the chassis is elevated;

Figure 7 is a similar view in the lower position 10 of the chassis;

Figures 8 and 9 are details of Figure 3, and Figure 10 is a section on the line 10—10 of Figure 6.

Reference to these views will now be made by 15 use of like characters which are employed to designate corresponding parts throughout.

In Figure 1 is shown diagrammatically an endless overhead chain conveyor 1 for carrying work to and taking it from a plating apparatus 2. 20 The chain conveyor 1 carries spaced work pushers 3 which move the work along a rail as will presently be shown. The plating machine embodies an endless series of tanks 4 and a rail designated by the numeral 5. Work is moved along 25 the rail 5 by a chain conveyor or a reciprocating pusher bar as shown for example in the copending application of John V. Davis, Serial No. 755,365, filed June 18, 1947. This conveyor, which need not be detailed here, may move the work 30 in either direction with respect to the direction of the conveyor 1. A loading and unloading mechanism between the two conveyors is designated generally by the numeral 6 and may be constructed as shown in the copending application 35 of John V. Davis, Serial No. 181,650, filed August 26, 1950.

The invention is concerned with lowering the work from the conveyor 1, dipping it into one or 40 more tanks 7 and returning it to the same conveyor. This is a non-electrolytic process such as a cleaning operation. Although the invention is not necessarily associated with plating, it is particularly economical in connection therewith. Ordinarily the non-electrolytic operations are 45 incorporated in the plating machine. Where a loading and unloading conveyor is used, as here, it affords ample floor space for non-electrolytic operations, and the mechanism for such operations can be built more cheaply in this conveyor 50 than in the plating machine.

The conveyor 1 embodies a rail 10 disposed below the chain 11 and following the same path. The pushers 3 are joined to selected pivot pins 12 of the chain 11 and ride on the rail 10. Hooks 55 or carriers 13 are suspended from the rail and are advanced by the pushers as known in the art.

Adjacent to the tanks 7 is an elevator for raising and lowering a separable segment of the rail 10. This segment, as will be described, extends over both tanks, so that work may be moved onto one end of the segment, lowered, dipped into the tanks, moved along the tanks, elevated to the main rail and finally discharged from the segment to the rail proper.

The elevator embodies a suitable framework which may include a number of hollow posts or columns 15 braced by suitably positioned longitudinal members 17. To the inner surface of each of the end columns is secured a vertical track 18 for guiding the aforementioned movable rail segment. Carriages 19 are provided at the respective tracks and are joined by a chassis member 20. Each chassis carries a pair of rollers 21 that ride in the track and another pair 22 that ride on the edges of the track 18.

A series of transverse arms 23 are secured to the member 20 in spaced relation to each other and carry the aforementioned movable rail segment which is now identified by the numeral 10'.

The arms 23 carry a set of aligned bushings 24 in which is slidably mounted a rod 25 parallel to the rail section 10'. The ends of the rod 25 carry rollers 26, 27 engageable respectively with cams 28 and 29 mounted on the end columns 15. A longitudinal member 30 is secured across the arms 23 to brace the structure and for another purpose that will presently be described. The cams are positioned at different levels and both slope upwardly in the direction of work travel. The lower cam 28 has its lower end positioned to be engaged by the roller 26 when the vertically movable chassis with the rail section 10' is in its lower position, dipping the work in the tanks 7.

A vertical hydraulic cylinder 31 is mounted substantially at the center of the frame structure. The piston rod 32 exposed through the upper end of the cylinder is secured to an angle iron 33 which in turn is welded to the longitudinal member 20 of the movable chassis. Sprocket wheels 34 are mounted on the upper ends of the end columns 15. Over each sprocket wheel is passed a sprocket chain 35 having one end connected to a counterweight 36 mounted in the adjacent column 15. The other end of the chain is fastened to a plate 37 welded in the member 20 as a means of connecting the chain to the member 20. A bracket 38 is attached to each of the end columns 15 near the upper end thereof and receives a rod 39 adjustable vertically therein by a pair of nuts 40. The rod 39 is in the upward path of the member 20 and is a stop for the upward movement of the chassis. The stops are adjusted to bring the movable rail 10' in accurate alignment with the fixed rail 10.

Work is displaced from the fixed rail 10 to the movable section 10' for immersion in the tanks 7. Timed mechanism, known in the art, is provided to stop the chain 1 and relieve the pressure in the cylinder 31 to permit the chassis to drop. After a proper interval the same mechanism charges the cylinder to raise the chassis and again advance the work. During these movements the carriers 13 on the rail section 10' are liable to be thrown out of vertical alignment with the overhead pushers 3. The causes of the misalignment may be the manner in which the work pieces hit the solution, momentum of the work carriers when the chain stops, vibration in the apparatus or in other machines in the shop, and the like. In many cases the carriers on the movable rail section will strike the pushers rather

than take a position in front of them, and the result is an interruption in the smooth functioning of the apparatus.

To correct this condition a number of rocker arms 41 are pivotally mounted as first class levers on the pivot bar 30 by means of pins 42. At the pusher bar 25, each rocker arm has a lengthwise slot 43 receiving a pin 44 on the pusher bar. Near the opposite end, at the rail section 10', the rocker arm has a vertical finger 45 adapted to swing against the corresponding pusher 3 as shown in Figure 10.

The cams 28, 29, as stated, slope upwardly in the direction of the chain travel. The cam 28 is so positioned that its lower end is engaged by the roller 26 of the reciprocating rod 25 when the chassis is in its lower position. The bar 25 is thereby shifted rearward, swinging the finger 45 forward, in the direction of work travel, and positively holding the engaged hooks 13 against slipping out of proper registration with the overhead pushers 3. As the chassis rises, there is no danger of work slippage. The bar does not shift until its roller 27 engages the upper cam 29. The bar 25 then commences to shift in the direction of chain travel until the roller 27 reaches the high point of the cam 29, at which time the chassis has reached its uppermost position. The bar 25 swings the rocker arms 41 in the same direction and the fingers 45 are moved in the opposite direction or rearward with respect to the direction of chain and work travel. This is an idle movement that does not displace the hooks but merely sets the arms 41 for another operation on the downward movement as described.

On descent of the chassis, there is no movement of the rod 25 until the roller 26 engages the cam 28. At the bottom of the movement, the rocker arms 41 again advance and hold the hooks against displacement.

The invention is also applicable to other apparatus wherein the work is moved by a separable rail section away from the main rail for treatment. Also, the treating apparatus is not necessarily below the rail and may lie spaced therefrom in any direction transverse of the rail. The claims are to be understood accordingly.

Although a specific embodiment of the invention has been illustrated and described, it will be understood that various alterations in the details of construction may be made without departing from the scope of the invention as indicated by the appended claims.

What I claim is:

1. In a conveying apparatus, a work-supporting rail, a chain movable along said rail, pushers on said chain for moving work along said rail, a frame structure adjacent to said rail, a chassis mounted for movement in said structure transversely of said rail, means for moving said chassis, said rail having a separable section carried by said chassis, a work-treating apparatus spaced transversely from said rail at said section for operating on work pieces carried by said section, a work-moving member movably mounted on said chassis, said member having a portion positioned adjacent to said section to engage a work carrier thereon, and means operable on movement of said chassis toward said treating apparatus for moving said portion in the work-advancing direction.

2. In a conveying apparatus, a work-supporting rail, a chain movable along said rail, pushers on said chain for moving work along said rail, a frame structure adjacent to said rail, a chassis

mounted for movement in said structure transversely of said rail, means for moving said chassis, said rail having a separable section carried by said chassis, a work-treating apparatus spaced transversely from said rail at said section for operating on work pieces carried by said section, a work-moving member movably mounted on said chassis, said member having a portion positioned adjacent to said section to engage a work carrier thereon, an actuating member for said work-moving member carried by said chassis, and an operating member carried by said structure and engageable by said actuating member on movement of said chassis toward said treating apparatus for moving said portion in the work-advancing direction.

3. In a conveying apparatus, a work-supporting rail, a chain movable along said rail, pushers on said chain for moving work along said rail, a frame structure adjacent to said rail, a chassis mounted for movement in said structure transversely of said rail, means for moving said chassis, said rail having a separable section carried by said chassis, a work-treating apparatus spaced transversely from said rail at said section for operating on work pieces carried by said section, a rod slidably mounted on said chassis parallel to said section, a work-moving member connected to said rod and to said chassis, one of the connections being a pivotal connection and the other being a slot-and-pin connection, said member having a portion positioned adjacent to said section to engage a work-carrier thereon, and means operable on movement of said chassis toward said treating apparatus for sliding said rod and effecting a work-advancing movement of said portion.

4. In a conveying apparatus, a work-supporting rail, a chain movable along said rail, pushers on said chain for moving work along said rail, a frame structure adjacent to said rail, a chassis mounted for movement in said structure transversely of said rail, means for moving said chassis, said rail having a separable section carried by said chassis, a work-treating apparatus spaced transversely from said rail at said section for operating on work pieces carried by said section, a rod slidably mounted on said chassis parallel to said section, a work-moving member connected to said rod and to said chassis, one of the connections being a pivotal connection and the other being a slot-and-pin connection, said member having a portion positioned adjacent to said section to engage a work-carrier thereon, an operating member for said rod carried by said structure and engageable by said rod on movement of said chassis toward said treating apparatus for sliding said rod and effecting a work-advancing movement of said portion.

5. In a conveying apparatus, a work-supporting rail, a chain movable along said rail, pushers on said chain for moving work along said rail, a frame structure adjacent to said rail, a chassis mounted for movement in said structure transversely of said rail, means for moving said chassis, said rail having a separable section carried by said chassis, a work-treating apparatus spaced transversely from said rail at said section for operating on work pieces carried by said section, a rod slidably mounted on said chassis parallel to said section, a work-moving member connected to said rod and to said chassis, one of the connections being a pivotal connection and the other being a slot-and-pin connection, said member having a portion positioned adj-

cent to said section to engage a work-carrier thereon, a cam carried by said structure and engageable by said rod on movement of said chassis toward said treating apparatus for sliding said rod and effecting a work-advancing movement of said portion.

6. The construction defined in claim 1 further characterized by setting means for said member operable on movement of said chassis toward 10 said rail.

7. The construction defined in claim 3 further characterized by reversing means for said rod carried by said chassis and operable on movement of said chassis toward said rail.

8. The construction defined in claim 5 further characterized by another cam carried by said structure and engageable by said rod on movement of said chassis toward said rail for sliding said rod in the opposite direction.

20 9. In a conveying apparatus, a work-supporting rail, a chain movable along said rail, pushers on said chain for moving work along said rail, a frame structure adjacent to said rail, a chassis mounted for movement in said structure transversely of said rail, means for moving said chassis, said rail having a separable section carried by said chassis, a work-treating apparatus spaced transversely from said rail at said section for operating on work pieces carried by said section, 25 a rod slidably mounted on said chassis parallel to said section, a work-moving member connected to said rod and to said chassis, one of the connections being a pivotal connection and the other being a slot-and-pin connection, said member having a portion positioned adjacent to said section to engage a work-carrier thereon, said rod lying between said rail section and the connection to the chassis, and means operable on movement of said chassis toward said treating apparatus for 30 sliding said rod and effecting a work-advancing movement of said portion.

35

40

10. In a conveying apparatus, a work-supporting rail, a chain movable along said rail, pushers on said chain for moving work along said rail, a frame structure adjacent to said rail, a chassis mounted for movement in said structure transversely of said rail, means for moving said chassis, said rail having a separable section carried by said chassis, a work-treating apparatus spaced transversely from said rail at said section for operating on work pieces carried by said section, a rod slidably mounted on said chassis parallel to said section, a work-moving member connected to said rod and to said chassis, one of the connections being a pivotal connection and the other being a slot-in-pin connection, said member having a portion positioned adjacent to said section to engage a work-carrier thereon, said rod lying between said rail section and the connection to the chassis, an operating member for said rod carried by said structure and engageable by said rod on movement of said chassis toward said treating apparatus for sliding said rod and effecting a work-advancing movement of said portion.

work advancing movement of said portion.

11. In a conveying apparatus, a work-supporting rail, a chain movable along said rail, pushers on said chain for moving work along said rail, a frame structure adjacent to said rail, a chassis mounted for movement in said structure transversely of said rail, means for moving said chassis, said rail having a separable section carried by said chassis, a work-treating apparatus spaced transversely from said rail at said section for operating on work pieces carried by said section, a rod slidably mounted on said chassis parallel to said section, a work-moving member connected

to said rod and to said chassis, one of the connections being a pivotal connection and the other being a slot-and-pin connection, said member having a portion positioned adjacent to said section to engage a work-carrier thereon, said rod lying between said rail section and the connection to the chassis, a cam carried by said structure and engageable by said rod on movement of said chassis toward said treating apparatus for sliding said rod and effecting a work-advancing movement of said portion.

12. The construction defined in claim 11 further characterized by another cam carried by

5
10

said structure and engageable by said rod on movement of said chassis toward said rail for sliding said rod in the opposite direction.

CHESTER GRAHAM CLARK.
